UNITED STATES PATENT OFFICE.

STEPHEN A. MARKER, OF NEWARK, NEW JERSEY.

SUSPENSORY.

1,347,864.

Specification of Letters Patent. Patented July 27, 1920.

Application filed January 3, 1918. Serial No. 210,210.

To all whom it may concern:

Be it known that I, STEPHEN A. MARKER, a citizen of the United States, residing in Newark, county of Essex, State of New Jersey, have invented certain new and useful Improvements in Suspensors, of which the following is a full and clear specification.

My invention relates to improvements in anatomical suspensors, and particularly to 10 that class of suspensors intended for the support of the scrotum.

The main object of the present invention is to improve suspensor supporters in a manner to make them light, strong, durable 15 and easily applied and maintained in proper position and also more sanitary, that is so that the several parts comprising the suspensor can be detached one from the other and the parts requiring renewal or cleansing 20 readily handled for that purpose.

Another object of the invention is to so arrange and connect the several parts that they can be worn either under or over an undergarment, this being a matter wholly 25 within the liking of the wearer.

With these and other objects, I have devised and arranged a suspensor of the character described that will meet all the present requirements, as will be hereinafter 30 fully described in detail and the features of merit and novelty pointed out in the annexed claims.

In the accompanying drawings:

Figure 1 is a front elevation of my improved suspensor arranged and connected in a manner as applied to the wearer.

Fig. 2 is a side elevation of the same, part of the band being broken away.

Fig. 3 is a detail showing how the clasps 40 are secured to the leg or crotch straps.

Fig. 4 is a detail of the ends of the crotch straps showing a loop for connecting said straps to the sack.

Fig. 5 is a front elevation on a smaller 45 scale showing how the suspensor is applied over an undergarment.

In the preferred embodiment of my invention, 1 is the waistband which is adapted to encircle the body and support the several 50 parts comprising the suspensor. This band is usually made of some elastic material and joined by any suitable means, such as a buckle, clasp or as here shown, by means of snap fasteners. 2 is a semicircular 55 member made of some firm material, such as leather or the like, and is detachably fas-

tened to the waistband by means of a clasp 3. The member 2 is provided with loops 5 through which pass and by which is held an elastic loop 6. This loop is preferably made 60 of rubber tubing and has secured in the ends thereof clasps 6'. The sack is shown at 10 and may be of any suitable fabric or webbing best suited for the purpose. It is shaped as shown in Figs. 1 and 2 to give 65 the best supporting conditions for the scrotum. The frontal opening 12 for the penis is properly located and preferably bound with a soft tape, as shown at 13. The upper part of the sack has a yoke 15 of firmer fabric than the sack material fastened thereto and in turn said yoke is provided at its top with a strong piece of material 16, such as leather, canvas or the like and to which in any desirable manner are fastened clasp buttons 17. These buttons are adapted to be engaged by the clasps 6' carried by loop 6. The leg or crotch straps 20 can be made of any desired material but I have shown them as made of rubber tubing. Secured to the 80 upper ends of said straps, as hereinafter described, are clasps 21 which pass over and engage buttons 22 on the waistband 1. I have provided two sets of buttons 22 so that a desirable tension and adjustment of said 85 straps 20 can be made. The lower ends of the leg straps are fastened to an eye 25 as shown in Fig. 4, said eye in turn attached to a hook 26 fastened to the bottom of the sack, as shown in Fig. 2. This may be any 90 kind of a standard hook, such for instance as the well known hump hook or the like so that the straps can be readily detached from the sack but will under normal conditions remain attached.

The leg or crotch strap 20 I prefer to make of standard rubber tubing thereby giving a more sanitary and at the same time more comfortable support. By using rubber tubing I am also enabled to make 100 a crotch strap that can be altered to fit and suit the wearer. The clasp 21 is secured to the tubing 20 by having the free ends 21' of said clasp capable of engaging each other at the extreme ends and bent to form a loop 21^a near said ends. The ends of the clasp are contracted between the loop 21^a and the large opening of the clasp as shown at 21^b. Thus it will be seen that when the free ends of the clasp are forced into the tubing the 110 loop 21^a will tend to expand the same, and continued movement of the tubing over

the clasp will cause said tubing to follow the form of the ends of the clasp and rest within the contracted portion 21^b of the clasp, as shown in Fig. 3. 5 When the clasp is forced within the tubing as here shown it will be securely held against any strain it will be subjected to in retaining the sack in desired position. By fastening the clasp to the tubing in this 10 manner the wearer is enabled to readily make alterations in the length of the tubing by simply removing the clasp, cutting off a portion of the tubing and reinserting the clasp in the manner shown and described. 15 The clasps 6' may be fastened to loops 6 in the same manner as clasps 21 are fastened to the straps 20. In Fig. 4 I have shown in dotted lines a modified manner of forming the free end of the loop 25 to the tubing 20, 20 the result however being the same. It can be readily understood that the manner of enlarging the free ends of the clasp so that they will be retained within the tubing can be varied to best suit the form of clasp to be employed.

In Fig. 5 I have shown the suspensory in position to be applied to the wearer with part of the same over and part under an undergarment. In this application it will be noticed that waistband 1 and the number 30 2 are on the outside of the undergarment 30, while the sack 10 is underneath the same and directly engaging the scrotum. The clasps 6' engage the buttons 17 on the yoke 35 15 of the sack through the undergarment, thereby holding it in place in the same manner as shown in Fig. 1. The crotch straps or tubes 20 pass around the thighs over the undergarment and are free to be fastened 40 to the waistband in the same as shown in Fig. 1. Thus it will be seen that in order to remove the suspensory and the undergarment, clasp 3 is unfastened from the waistband, clasps 21 on the crotch straps 45 from buttons 22, and waistband 1 unfastened and the undergarment removed still having attached thereto the sack, member 2 and crotch straps or tubes 20. It will be further noticed that when the undergarment is again placed on the wearer the sack 10 will be in the desired position after the waistband is attached and clasps 3 and 21 are attached to said waistband, so that once the sack is properly adjusted and attached to the undergarment it will remain 50 so until the undergarment is discarded.

If so desired the wearer can apply all parts of the suspensory directly to the body beneath the undergarment. When the suspensory is worn in this manner the several parts are attached and clasped together in the same manner as when worn partly over

the undergarment, the main difference being that the buttons 17 are directly engaged by clasps 6' instead of including the interposed 65 undergarment.

By arranging and constructing a suspensory in the manner herein described, I am able to replace any and all parts when worn out or broken and also remove the parts for 70 necessary cleansing, thereby keeping the suspensory in a desirable condition of usefulness.

By having the abdominal member 2 capable of being detached from the waistband 75 and the sack, I am enabled to give the wearer the choice of wearing the suspensory either partly over the undergarment or wholly under the undergarment, thereby 80 making a condition of adjustment and comfort in wearing optional with the wearer.

Of course it should be understood that the relative proportions and shapes of the several elements can be varied to suit the 85 conditions and requirements demanded in the construction of my invention:

I claim:

1. A suspensory comprising a flexible waistband, a sack, a member intermediate to said waistband and sack, an elastic element 90 freely supported by said intermediate member, clasps on the free ends of said elastic element for engaging and holding the sack, a waistband clasp for fastening the intermediate member to the waistband, whereby 95 said intermediate member can be detached from the waistband, and crotch straps detachably fastened to the lower edge of the sack and their free ends capable of being detachably engaged by the waistband. 100

2. A suspensory comprising a waistband, a sack, crotch straps of rubber tubing, and clasps having one end of enlarged formation, capable when forced within the tubing of expanding said tubing in a manner to be 105 retained in desired position and said clasps adapted to detachably engage the waistband and sack.

3. A suspensory comprising a waist band, a sack, crotch straps composed of rubber tubing, and eyelet joining two ends of said tubing and adapted to detachably engage the sack, and clasps retained within the open ends of said tubing for detachably engaging the waistband. 110

4. A suspensory comprising a waistband, a sack, means for uniting said parts, crotch straps composed of rubber tubing, and clasps formed in a manner to be thrust into the opening in said tubing and be retained in desired position by the pressure of the tubing on the clasp. 120

STEPHEN A. MARKER.
